UNITED STATES PATENT OFFICE.

WILLIAM G. TEMPLETON, OF COLORADO SPRINGS, COLORADO.

VENDING-MACHINE.

1,294,194.

Specification of Letters Patent.

Patented Feb. 11, 1919.

Application filed June 18, 1917. Serial No. 175,440.

To all whom it may concern:

Be it known that I, WILLIAM G. TEMPLETON, a citizen of the United States, residing at Colorado Springs, in the county of El Paso and State of Colorado, have invented certain new and useful Improvements in Vending-Machines; and I do hereby declare the following to be a full, clear, and exact description of the same, reference being had 10 to the accompanying drawings, forming part of this specification.

This invention relates to a vending machine and more especially to that type of machine which is adapted, upon manipulation 15 of suitable release mechanism, to deliver stamps, coupons, tickets, or other similar articles. One of the essential objects of the invention is the provision of a machine of large capacity and exceedingly efficient 20 construction which will successfully handle such articles when the latter are connected together, in the form of a sheet or sheets, and which will effect the delivery of said articles individually or in groups successively detached from the sheet or sheets.

With the above and other objects in view, the invention consists in certain combinations, arrangements and constructions of parts hereinafter described in a preferred 30 form and particularly pointed out in the claims at the end of the specification.

In the drawings:

Figure 1 is a front elevation of a vending machine constructed in accordance with the 35 present improvements.

Fig. 2 is a top plan view of the same with the upper casing removed.

Fig. 3 is a horizontal section through the vertical frame which supports the sheet of 40 connected articles, the view being in a plane indicated by the line 3-3 of Fig. 1.

Fig. 4 is a central vertical section of the machine on the line 4-4 of Fig. 3, looking toward the right hand side of the machine, 45 as indicated by the arrow.

Fig. 5 is a central vertical section of the lower portion of the machine taken substantially in the same plane as that of Fig. 4, but looking toward the left.

Fig. 6 is a front elevation of the lower portion of the machine with the front wall of the base casing removed.

Fig. 7 is a horizontal section of the upper portion of the base casing taken on the 55 line 7-7 of Fig. 6.

Fig. 8 is a horizontal section of the lower

portion of the base casing taken on the line 8-8 of Fig. 6.

Fig. 9 is a vertical section through lower casing taken on the line 9-9 of Fig. 7. 60

Fig. 10 is a detail section on the line 10-10 of Fig. 9.

Like characters of reference in the several figures indicate the same parts.

The machine adopted for illustrating the 65 invention is one designed especially for the vending or delivery of stamps, and it is adapted for handling the ordinary sheets of stamps, such as are printed with ten columns or vertical rows in a sheet. In the 70 present specific embodiment, it is preferred that the machine deliver a number of stamps at each operation, although, as will hereafter appear, the machine may deliver a single stamp at each operation without 75 mechanical change. The sheets of stamps are incorporated in the machine in a pile, one above the other, with the rows of stamps of the several sheets in registry with each other, and at each operation of the machine 80 a group of stamps will be detached from the pile of sheets and delivered to the person operating the machine. For the purposes of the present application, however, it will be sufficient to describe the machine as designed for handling a single sheet of stamps 85 which are detached individually from successive horizontal rows.

Before describing in detail the mechanism of the machine adopted for illustrating the invention, it may be stated briefly 90 that the machine embodies sheet supporting and feeding means, consisting of a rotary drum mounted on a vertical axis within a suitable upper casing. The sheet of 95 connected articles or stamps is adapted to descend by gravity axially of the drum to position successive horizontal rows of the articles in the sheet, after the several articles of successive rows have been severed 100 individually. Provision is made for imparting a step-by-step rotation to the drum to advance the articles of the lowermost horizontal row successively into the path of the severing mechanism, the feeding movement taking place preferably during the return movement of the parts of the severing mechanism to their normal position. With this arrangement, an article will be 105 properly positioned for severing on the next operation of the severing mechanism. It is, therefore, possible to employ a greatly sim-

plified severing mechanism, since only one set of severing knives is required, with the additional advantage that the release mechanism by which the severing knives or cutters are controlled is also greatly simplified.

In its preferred construction the severing device embodies a movable cutter projecting axially from a horizontal shaft and provided with a vertical and a horizontal knife, said 10 knives of the movable cutter being coöperable with fixed vertical and horizontal knives. The horizontal shaft is adapted to be rotated forwardly so as to carry the movable knives past the fixed knives at each 15 operation of the machine. For this purpose the shaft on which the movable cutter is mounted is normally locked against movement, but may be released by the deposit of a coin in the machine. When the shaft is 20 released, it may be operated manually in such manner that the movable knives will be carried past the severing point, and effect severance of an article from the lowermost row of articles supported by the drum. An 25 incomplete forward rotation of the shaft will result in the parts being locked in such position that the movement must be completed before the machine will be again locked and before another coin can be 30 brought into position to operate the releasing mechanism. With this construction, it becomes practically impossible to manipulate the machine in such manner as to cause the delivery or severance of a second article 35 before the complete delivery of the article which should have been delivered by the first operation of the machine. The mechanism for accomplishing these results is of an exceedingly simple character, but at the same 40 time the parts thereof are so constructed that a false operation of the machine is practically impossible.

Referring particularly to the drawings, it will be noted that from a base casing 1, a 45 drum 2 projects upwardly, said drum being substantially cylindrical in form and extending downwardly a short distance into the base casing 1, through an opening 3 in the top wall of the latter. The drum 2 is 50 inclosed within an upper casing 4 preferably provided with a transparent wall 5 and removably mounted on the base casing. For securing the upper casing in position on the base casing suitable clips 6 may be provided 55 in the top of the base casing, which clips are adapted to be rotated into engagement with the lower horizontal annular flange 7 of the upper casing, in the manner shown particularly in Figs. 1 and 3. The drum 2 is 60 journaled on a vertical axis or rod 8 supported upon the bottom of the base casing and said drum constitutes a vertical support for the sheet of connected articles or stamps adapted to be severed individually in succession upon each operation of the machine in 65

a manner to be described hereinafter. The sheet is adapted to be fed downwardly upon the drum by gravity through the medium of any suitable pressure means, preferably, however, by the weight of a clamping device 70 slidably mounted for axial movement on the drum.

The clamping device is adapted to retain the upper horizontal edge of the sheet of connected articles, for example, the upper 75 horizontal blank margin of a sheet of stamps, and as each horizontal row of the stamps of the sheet is severed, after successive operations of the machine, the clamping device causes the sheet to descend on the drum in 80 order to position a fresh horizontal row of stamps for severing and delivery. The clamping device includes in its construction a substantially ring-like member 9, slidably mounted on the drum, the ring being split 85 and the opposite vertical edges 10 thereof spaced apart, as shown, but connected together toward their upper ends by means of a horizontal connecting strip 11. Formed on the drum is a vertically extending flanged 90 strip 12, the opposite vertical flanges 13 of which are spaced from the peripheral surface of the drum, as shown in Fig. 3. Said strip 12 may be secured in any preferred manner to the vertically-extending laterally-projecting flanged portions 14 of the cylindrical wall of the drum, and the flanges 14 95 form stops or abutments against which the opposite vertical edges of a sheet of stamps may engage, when the sheet is wrapped 100 around the drum. The vertical strip 12 constitutes a guideway for the ring 9 of the clamping device, and prevents the latter from rotary movement relatively to the drum, although permitting axial movement 105 of the ring. For this purpose, the horizontal connecting piece 11 is provided with opposite inwardly extending inner flanged portions 11^a which are respectively adapted to 110 underlap the opposite flanges 13 of the vertical strip 12. Hinged to the opposite vertical edges of the connecting piece 11 are substantially semi-cylindrical clamping members 15 which are adapted to swing outwardly on their hinges to permit the wrapping of the sheet of stamps around the ring 9 and the clamping device. In order to secure the sheet of stamps to the ring 9, the semi-cylindrical hinged members 15 may be 115 swung inwardly on their hinges, and locked together by a spring clamping means consisting, in the present embodiment, of a coil spring 16 secured to one of the members 15 and provided with a lug 17 at its outer end which may be inserted into a hook 18 formed 120 on the other member. If desired, the ring 9 may be provided with a roughened outer surface preferably attained by securing a strip of abrasive material such as sand paper, for example, to the outer surface of the ring. 125 130

With this construction a sheet of stamps secured to the ring by the hinged members 15 will be effectually prevented from slipping around the ring.

- 5 Pivottally mounted on the upper end of the drum 2 is a retaining member 19 consisting of a suitable horizontal strip located above the drum and provided with hooks 20 which are respectively adapted to engage pins 21 projecting from the ring 9 and connecting piece 11, for maintaining the clamping device in elevated position when wrapping a sheet of stamps around the drum. The latter operation may be readily effected 10 by removing the upper casing 4 and swinging the hinged clamping members 15 to open position, then wrapping the sheet around the ring 9, with the opposite edges of the sheet so positioned as to engage the flanged portions 15 projecting radially from the cylindrical wall of the drum. The sheet will also be so positioned that the top horizontal line of perforations between the upper row of stamps and the blank margin is located 20 somewhat beneath the lower edge of the ring 9, and will be securely fastened on the ring by closing the hinged members 15 and securing them in closed position by means of the spring clamp above described.
- 25 30 After the sheet has been thus secured to the clamping device it is essential that the retaining member 19 be released in order to permit the clamping device to descend axially of the drum and position a new horizontal row of stamps for severing after each 35 row is depleted, because of previous operations of the machine. For releasing the retaining member 19, it is provided with an upwardly inclined arm 22, which is engaged by the top of the upper casing 4, when 40 the latter is mounted in position over the drum. The engagement of the top of the upper casing with said upstanding arm 22 will move the hooks 20 of the retaining 45 member in such manner as to release them from the pins 21 and thereby permit the clamping device to fall by gravity as occasion requires. When the upper casing is removed, the retaining member 19 moves by 50 gravity into locking position.

55 Positioned beneath the lower end of the rotary drum 2 is a horizontal table 23 secured in any preferred manner to the side walls of the base casing and provided with a slot 24 in which works a rotary cutter 25. The horizontal table 23 is spaced from the lower edge of the rotary drum a distance substantially equaling the vertical dimension of a stamp in the sheet, and the 60 bottom row of stamps is located between the lower edge of the rotary drum and the table 23. The cutter 25 projects radially from a horizontal shaft 26 journaled in the side plates of the base casing and is adapted 65 to be rotated forwardly to sever an in-

dividual stamp from the sheet of stamps positioned between the lower edge of the drum and the table. Secured to the cutter 25 are a vertical knife 25^a and a horizontal top knife 25^b, which knives coöperate with fixed 70 knives when the cutter is moved past the severing point in the operation of the shaft 26. The horizontal fixed knife 205 is secured beneath a horizontal supporting bar 206 extending between the side walls of the 75 base casing and the vertical fixed knife 207 is secured to a bar 208 depending from said horizontal supporting bar 206. On forward movement of the shaft, the rotary cutter severs the end stamp of the lower 80 most row of stamps and throws the stamp forward into a delivery chute, which will be hereinafter described.

85 For operating the shaft 26 it is provided near its right hand end with an operating lever 27, the latter having its inner end 27^a of a disk-like formation where it surrounds the shaft and its outer end 28, which projects through a slot 29 in the front wall of the base casing, in the form of a finger piece 90 adapted to be depressed at each operation of the machine. Pivottally mounted on the disk-like inner end 27^a of the operating lever is a locking pawl 30 having its forward end 31 counterweighted and its rear end provided with a locking hook or shoulder 32 which is adapted to engage a locking projection 33 secured to the right-hand side wall of the base casing. Preliminary to the operation of the shaft, the rear end of 95 the locking pawl must be depressed against the action of its counterweight in order to release said rear end from the locking projection. In the present embodiment this is 100 preferably accomplished by the introduction of coin into the machine. The coin is introduced through a coin slot 34 in the top of the base casing and travels thence down an incline 35 onto a ledge 36 formed on the rear end of the locking pawl to depress 105 the latter and release the hook of said locking pawl from engagement with the locking projection. If the coin be of light weight, it passes off the ledge of the locking pawl through a discharge opening 38 at the 110 rear end of the coin deposit chute and thence through a return chute 39 which communicates at its forward end with a discharge slot 40 in the front wall of the base casing, whereby a coin of light weight may be 115 returned to the person to whom it belongs.

120 Assuming that the locking pawl is released by the deposit of a coin of proper denomination in the machine, the operating lever may be depressed and in its forward movement it will operate the cutter to sever a stamp from the bottom row of stamps located above the horizontal table. During the forward movement of the cutter the coin drops off the ledge 36 at the 125 130

rear end of the locking pawl and falls through a chute 41 into a suitable storage receptacle 42 in the bottom of the fixed casing. A spring 43 secured at one end 5 to the disk-like portion of the operating lever and at the other end to the bottom of the base casing acts to return the shaft and cutter to normal position.

Near the bottom of the drum the sheet of 10 stamps passes within clamping members consisting preferably of a pair of ring-like members 44 pivotally mounted at their proximate ends on a supporting ring 45 secured to the drum and connected together 15 by a coil spring 46 which acts to urge the clamping members 44 toward the surface of the drum and thereby clamp the sheet above the lowermost row which is being severed by successive operations of the 20 cutter.

In order to advance each stamp of the lower row of stamps into the path of the cutter into position for being severed on forward movement of the latter, provision 25 is made whereby a step by step movement may be imparted to the drum, a one-step advance of the drum being sufficient to feed a single stamp of the bottom row into the path of the cutter. This feeding 30 movement is preferably effected while the operating shaft and the cutter are being returned to their normal position, and may be accomplished by means of the following instrumentalities:—Secured to the vertical 35 shaft or axis 8 of the rotary drum 2 is a ratchet preferably constructed in the form of a disk 47 disposed in a substantially horizontal plane and provided with a plurality of detents 48 corresponding in number 40 to the number of stamps in the lowermost horizontal row of stamps mounted on the drum. In the present machine the detents 48 are ten in number, as the machine has a capacity for ten vertical rows 45 of stamps on the drum 2. The detents 48 are disposed in a circular path about the disk 47 and are in the form of slots cut from the material forming the disk. The edge of each slot is cut in such manner as 50 to provide an outer angular projection 49 extending inwardly with respect to the periphery of the disk and having its opposite edges 49^a converging to a point 49^b. Said angular projection 49 constitutes a 55 stop which forms one member of a means for arresting the movement of the ratchet when a stamp of the lowermost row of stamps has been positioned in the path of the cutter 25. The ratchet 47 is held at 60 all times against rotation in one direction, i. e., toward the left as viewed in Fig. 8, by means of a stop pawl consisting of a spring arm 50 secured to the left hand side wall of the base casing and adapted to engage 65 in any one of the several detents 48.

Secured to the main operating shaft 26 is a depending arm 51 and pivotally mounted on the lower end of the arm 51 is an operating pawl 52 provided at its rear or inner end with a hook 53 adapted to engage in 75 any one of the slots or detents of the ratchet 47. The forward end of said operating pawl is connected to the horizontal supporting bar 206 by means of a coil spring 54 which functions to normally 75 depress the rear end of the operating pawl and maintain the hook 53 thereof within one of the detents or slots 48, in the manner shown in the drawings. On forward movement of the main operating shaft 26, 80 i. e., whenever the operating lever 27 is depressed, the depending arm 51 is rotated rearwardly and the hook 53 of the operating pawl 52 is thereby moved out of engagement with one of the detents or slots 85 48 in which the hook was positioned prior to the forward rotation of the operating shaft 26. During the release movement of the operating shaft, however, the depending arm 51 is rotated forwardly thereby 90 imparting a forward movement to the operating pawl 52. The spring 54 serves to depress the lower end of the operating pawl 52, thereby causing the hook 53 to enter the next detent or slot 48 of the disk 95 47, and as the return movement of the main shaft progresses, the engagement of the operating pawl 52 with the detent of the ratchet causes the latter to advance one step. While the ratchet is being advanced, it will be noted that the projections 49 are traveling in a circular path and consequently at the end of the movement of the ratchet the projection 49 of the slot receiving the hook 53 will engage the side of the operating pawl, thereby 100 arresting the movement of the ratchet, and also the rotary feeding drum 2. This serves to prevent the stamp which has been advanced into the path of the cutter from 105 being thrown out of proper alignment through momentum due to a rotation of the drum 2. After a one-step movement of the drum has been effected in the above set forth manner, the drum is locked against 110 forward rotation by means of the engagement of the angular walls 49^a, of the detent with the hook 53 of the operating pawl. The pawl 50 prevents reverse rotation at 115 all times.

The sheet being clamped immediately above the cutter by means of the clamping members 44, hereinbefore referred to, a full row of articles or stamps may be removed upon successive operations of the shaft 26 125 and then the clamping members 44 must be released in order that the sheet may feed downwardly to permit another row of stamps to be removed. This is accomplished by normally holding the clamps in clamp- 130

ing position by the spring 46 and, immediately after the cutter has removed the last stamp from the previous row, causing the clamping members 44 to be spread apart 5 against the tension of their spring by a clamp releasing member 55 pivotally mounted on the fixed ring 45 and positioned between the free ends of the clamping members 44. During the return movement incident to the severing of the last article from the lowermost row of stamps, a one-step movement is imparted to the drum and this causes the clamp releasing member 55 to engage a projection on the end of a rod 56 10 which engagement effects a pivotal displacement of the clamp releasing member 55 a sufficient distance to cause it to engage the opposite free ends of the clamping members 44 and spread them apart, thereby permitting the sheet of stamps to descend and present a new row of stamps for severance. Before the first stamp of the new row is severed, it is essential that the clamping members 44 be permitted to resume their normal 15 clamping position. For this purpose the rod 56 is pivotally mounted on a suitable depending supporting bar 57 and is adapted to be moved out of engagement with the clamp releasing member 55 before the cutter 20 25 has reached the severing point. Pivoted to the lower end of said rod 56 is a horizontal bar 58 provided at its inner end with a tooth 59 adapted to be engaged by a lug 60 carried by the shaft 26. A spring 61 connecting the forward end of the bar 58 with the supporting bar 57 normally maintains the tooth 59 of the horizontal bar 58 in engagement with the lug 60 of the shaft. On forward movement of the shaft a slight 25 30 rearward pull is transmitted to the horizontal bar 58 which likewise shifts the projection of the rod 56 forwardly so as to disengage said projection from the clamp releasing member 55. As the forward movement 35 40 of the operating shaft 26 progresses the lug 60 moves out of the tooth 59 and the spring 61 returns the horizontal bar 58 and the rod 56 back to normal position. Before this has occurred, however, the spring 46 connecting 45 50 the clamping members 44 has restored them to clamping position. In order to prevent an overthrow of the clamp releasing member 55, when the latter moves into engagement with the projection of the rod 56, the clamp 55 60 releasing member is slotted, as shown at 62, and within said slot 62 is positioned the free end of a stop pawl 63 pivoted on the ring 44 and provided with a projection 64 adapted to engage the face of the clamp releasing member 55.

It is desirable that the coin deposit slot in the top of the base casing be closed against the deposit of a coin during the movement of the operating lever 27. This 65 prevents insertion of a new coin or other-

wise tampering with the parts, before a complete operation of the machine has been effected. For this purpose a slide 65 is provided having an opening 66 adapted normally to register with the coin slot, *i. e.*, 70 when the said operating lever is depressed, the slide being held in such registering position by the lever engaging the vertical cam edge 67 of the slide, so as to cause the opening 66 of the slide to register with the coin deposit slot. When, however, the operating lever 27 is moved forwardly in the manipulation of the machine to sever and discharge a stamp, a spring 68 connecting the slide with the horizontal bar 206 moves the 80 latter so as to move the opening or slot 66 out of registry with the coin deposit slot. Thus, whenever the operating lever is moved away from its position of rest, the movement of the lever carries it out of engagement 85 with the cam edge 67 of the slide permitting the spring 68 to act and close the coin deposit slot.

The invention also provides a mechanism for closing the coin deposit slot against the 90 deposit of a coin when the supply of stamps mounted on the drum has been exhausted and the machine will be incapable of operation until the supply has been replenished. Pivoted at 69 on the horizontal supporting 95 bar 206 is a gate 70 provided with an upstanding projection 71, the latter having a cam face 72. Mounted on the clamping device which secures the upper edge of the sheet of stamps, is a pin 73 which, of course, 100 descends as the sheet of stamps becomes depleted owing to successive operations of the machine. When the last stamp of the last row has been removed, the one step movement imparted to the drum incident to the 105 return movement of the operating lever moves the pin 73 into engagement with the cam face of the gate and thereby shifts the latter beneath the coin deposit slot and closes the slot against the deposit of a coin. 110 When the supply of stamps has been replenished, the gate may be moved manually to open the slot.

In the manipulation of the machine should the person operating the lever 27 fail to depress the same the full distance necessary for severing a stamp and permitting the operating lever to return to its normal position under the influence of its return spring, there will be danger of the locking pawl becoming engaged with the locking shoulder 120 125 130 33, thus preventing subsequent movement of the operating lever so as to complete the movement of the shaft. In order to overcome this difficulty there is fixed to the left hand side plate of the base casing a rack bar 74 having on one edge a series of downwardly projecting teeth 75 and on its opposite side a series of upwardly projecting teeth 76. Pivots suspended from an up-

standing arm 77 secured to the shaft is a pawl 78 provided at its lower end with a stud 79 which is adapted to engage the teeth of the rack bar. The stud 79 is pressed into

- 5 engagement with said teeth by means of a spring 80 encircling the rack bar and bearing against said stud. With the above described construction, the stud 79 and the pawl may move downwardly only on one 10 side of the rack bar, *i. e.*, on the side having the downwardly projecting teeth 75, and may only move upwardly on the other side of the rack bar, *i. e.*, on the side having the upwardly projecting teeth 76. During the 15 forward movement of the operating lever the stud 79 is in engagement with the downwardly projecting teeth while, during the releasing movement of the operating lever, said stud is in engagement with the upwardly projecting teeth of the rack bar. Hence, an incomplete forward as well as an incomplete return movement of the operating lever will, through the engagement of the stud with the teeth of the rack bar, lock 20 the operating lever against movement in the opposite direction at the wrong time, and, as a result, the operating lever must be depressed the entire distance before it can be again returned to normal position.

- 30 Provision is made for operating a register each time a stamp or stamps is delivered. For this purpose the upstanding arm 77 of the shaft 26 is adapted normally to engage a register operating arm 81 and retain the 35 same in a position which, when the arm 81 is released, will permit the latter to operate a register 82. When the upstanding arm 77 is lowered incident to the forward movement of the shaft, the register operating arm is 40 released and actuates the register one space or one unit. During the return movement of the shaft the register operating arm is restored by the arm 77 to position for actuating the register on the next operation of 45 the machine.

The above described construction provides an apparatus for severing and delivering stamps which is of large capacity and is exceedingly efficient in operation. For example, by feeding the stamps into the path of the cutter at each operation of the machine, the cutting mechanism, as well as the coin controlled mechanism, is greatly simplified. The feeding and supporting drum for the 50 sheet of stamps may be enlarged without materially increasing the dimensions of the machine and the capacity increased to a great extent. For example, the drum may be constructed so as to be capable of supporting around its cylindrical wall a number of sheets arranged diametrically opposite to each other or in quadrature.

When a stamp has been severed it is carried forward by the cutter and deposited in 55 a suitable discharge chute 83 formed in the

front wall of the base casing whereby the severed stamp may be picked up by the person to whom it belongs.

What is claimed is:—

1. In a vending machine, of the class described, the combination of a fixed cutter, a single movable cutter having longitudinally and laterally extending cutting blades co-operable with said fixed cutter for severing an article from a sheet of articles connected to one another longitudinally and laterally of the sheet, means for advancing said movable cutter past the fixed cutter to sever an article from said sheet, means for returning the movable cutter to normal position, and feeding means actuated after an article has been severed for advancing the sheet of articles to position an article of the sheet in the path of the movable cutter. 70 75

2. In a vending machine of the class described, the combination of a fixed cutter, a single movable cutter having longitudinally and laterally extending cutting blades co-operable with said fixed cutter for severing an article from a sheet of articles connected to one another longitudinally and laterally of the sheet, means for advancing said movable cutter past the fixed cutter to sever an article from said sheet, feeding means actuated after an article has been severed for 80 advancing the sheet of articles to position an article of the sheet in the path of the movable cutter, and means for positively arresting the movement of said feeding means when the article has been advanced in 85 the path of the movable cutter. 90 95 100

3. In a vending machine of the class described, the combination of a fixed cutter, a single movable cutter having longitudinally and laterally extending cutting blades co-operating with said fixed cutter for severing an article from a sheet of articles connected to one another longitudinally and laterally of the sheet, normally inoperative means releasable by the deposit of a coin 105 in the machine for advancing said movable cutter past the fixed cutter to sever an article from said sheet, and feeding means actuated during each operation of the movable cutter for advancing the sheet of articles to position an article of the sheet in the path of the movable cutter. 110 115

4. In a vending machine of the class described, the combination of a movable member for supporting a sheet of connected articles, a fixed cutter, a movable cutter co-operating with said fixed cutter for severing an article from the sheet of connected articles, means for advancing said movable cutter past the fixed cutter to sever an 120 article from the sheet, means for returning the movable cutter to normal position, and means for moving the sheet supporting member during the return movement incident to each operation of the movable cut- 125 130

ter for advancing the sheet of articles to position an article of the sheet in the path of the movable cutter.

5. In a vending machine of the class described, the combination of a fixed cutter, a movable cutter coöperable with said fixed cutter for severing an article from a sheet of connected articles, means for advancing said movable cutter past the fixed cutter to sever an article from said sheet, a rotary drum for supporting the sheet of connected articles and movable step by step to advance an article of the sheet into the path of the movable cutter, and means for imparting a one step movement to said drum during each operation of the movable cutter.

6. In a vending machine of the class described, the combination of a fixed cutter, a movable cutter coöperable with said fixed cutter for severing an article from a sheet of connected articles, means for advancing said movable cutter past the fixed cutter to sever an article from said sheet, means for returning the movable cutter to normal position, a rotary drum for supporting the sheet of connected articles and movable step by step to advance an article of the sheet into the path of the movable cutter, and means for imparting a one step movement to said drum during the return movement incident to each operation of the movable cutter.

7. The combination with a movable cutter mounted on a horizontal axis for severing an individual article from a sheet containing rows of connected articles, of a drum rotatably mounted on a vertical axis for supporting the sheet of connected articles and movable step by step to advance the articles of the lowermost row of the sheet individually into the path of the movable cutter, means for imparting a one step movement to said drum during each operation of the movable cutter, and means movable axially on the drum when all the articles of the lowermost row have been severed for feeding the sheet to advance another row of articles into position for successive advancement into the path of the cutter.

8. The combination with a movable cutter mounted on a horizontal axis for severing an individual article from a sheet containing rows of connected articles, of a drum rotatably mounted on a vertical axis for supporting the sheet of connected articles and movable step by step to advance the articles of the lowermost row of the sheet individually into the path of the movable cutter, means for imparting a one step movement to said drum during each operation of the movable cutter, means movable by gravity on the drum when all the articles of the lowermost row have been severed for feeding the sheet to advance another row of articles into position for successive advancement into the path of the cutter, and guiding means on

the drum for preventing rotary movement of said gravitational feeding means relatively to the drum, while permitting axial movement of the gravitational feeding means.

9. The combination with a movable cutter mounted on a horizontal axis for severing an individual article from a sheet containing rows of connected articles, of a drum rotatably mounted on a vertical axis for supporting the sheet of connected articles and movable step by step to advance the articles of the lowermost row of the sheet individually into the path of the movable cutter, a clamping device movable axially on the drum for clamping the sheet above the upper row of articles, a removable casing adapted to surround the drum and means releasable when the removable casing is positioned on the drum for locking said clamping device in position at the upper end of the drum.

10. The combination of a movable cutter mounted on a horizontal axis for severing an individual article from a sheet containing rows of connected articles, of a drum rotatably mounted on a vertical axis for supporting the sheet of connected articles and movable step by step to advance the articles of the lowermost row of the sheet individually into the path of the movable cutter, means for imparting a one step movement to said drum during each operation of the movable cutter, means for clamping the sheet above the lower row of articles, means movable axially on the drum for feeding the sheet by gravity when said clamping means is released, and means for releasing said clamping means when the last article of the lowermost row of articles is severed.

11. The combination of a movable cutter mounted on a horizontal axis for severing an individual article from a sheet containing rows of connected articles, of a drum rotatably mounted on a vertical axis for supporting the sheet of connected articles and movable step by step to advance the articles of the lowermost row of the sheet individually into the path of the movable cutter, means for imparting a one step movement to said drum during each operation of the movable cutter, means for clamping the sheet above the lower row of articles, means movable axially on the drum for feeding the sheet by gravity when said clamping means is released, means for releasing said clamping means when the last article of the lowermost row of articles is severed, and means for restoring said clamping means to clamping position during the next operation of the movable cutter and before the latter has been advanced into severing position.

12. The combination with a movable cutter adapted to sever an article from a sheet

of connected articles, means for operating said cutter, a rotatable drum for supporting the sheet of connected articles and movable step by step to advance the articles of the sheet individually into the path of the movable cutter, and means for imparting a one step movement to said drum during each operation of the movable cutter, including a ratchet movable with the drum and provided with a plurality of detents, each formed with a stop, a pawl for engaging one of the detents of said ratchet to impart a one step movement to the drum, said stop being engageable with said pawl to limit the movement of the ratchet and drum, and a connection between the pawl and the cutter operating means for actuating said pawl during the return movement of the cutter.

13. In a vending machine of the class described, the combination of a movable member adapted to support a sheet of connected articles, a fixed cutter, a movable cutter coöperable with said fixed cutter, operating mechanism for advancing the movable cutter past the fixed cutter, to sever an article from the sheet of connected articles, and connections between the movable cutter operating mechanism and sheet supporting members for actuating the latter during each operation of the movable cutter to ad-

vance the sheet of articles to position an article of the sheet in the path of the movable cutter.

14. In a vending machine of the class described, the combination of a fixed cutter, a movable cutter having longitudinally and laterally extending cutting blades adapted to be advanced past said fixed cutter for severing an article from a sheet of articles connected to one another longitudinally and laterally of the sheet, feeding means adapted to advance the sheet of articles during each operation of the movable cutter to position an article of the sheet in the path of the movable cutter, and a main operating member for actuating both the movable cutter and feeding means.

15. In a vending machine of the class described, the combination of a fixed cutter, a movable cutter having longitudinally and laterally extending cutting blades adapted to be advanced past said fixed cutter for severing an article from a sheet of articles connected to one another longitudinally and laterally of the sheet and feeding means adapted to advance the sheet of articles after one article has been severed to position another article of the sheet in the path of the movable cutter.
